UNITED STATES PATENT OFFICE

2,439,943

CARD HANDLING DEVICE

Alfred M. Martin, Park Ridge, Ill.

Application August 7, 1943, Serial No. 497,834

6 Claims. (Cl. 129—16.7)

1

This invention relates to card handling device more particularly for use with card or loose leaf filing systems such as disclosed in my Patent No. 1,469,798 issued October 9, 1923 in which the record cards or leaves are mounted upright in a tray-like holder provided with transverse rails upon which the cards or leaves rest, the lower edges of the cards or leaves being notched or serrated to engage the rails, which may thus maintain the cards or leaves in echelon arrangement in the holder so that the cards or leaves are overlapped longitudinally of the holder with a margin exposed for indexing or other purposes.

As further disclosed in my said Patent No. 1,469,798, it is sometimes desirable to transfer a series comprising a considerable number of record cards (which term is hereafter intended to be understood to include record leaves or record sheets) from one compartment or space between adjacent partition supports to another such compartment or space, and to do this while maintaining the regularly overlapped or echelon arrangement of the cards, and the present invention, in one aspect, aims to disclose improved means for such purpose.

Furthermore, in addition to the transfer purpose referred to, it frequently becomes desirable to make a permanent record of a group or series of cards with their said margins exposed and displaying index and other informative data, and such permanent records may advantageously be made by photographing the card series. The present invention, therefore, provides means for removing an entire series of cards from the file in their regular echelon arrangement, for holding the cards while photographing the series, and for returning the series to the file, all without disturbing but rather maintaining said regular overlapped or echelon arrangement of the series.

These and other objects and advantages will be apparent from the following description taken together with the accompanying drawings, in which—

Figure 1 is a cross-sectional view taken on the line 1—1 of Fig. 2, but showing the cards in normal position;

Figure 2 is a longitudinal sectional view taken on the line 2—2 of Fig. 1, parts being shown in elevation, but showing a series of the cards on the mounting panel;

Figure 3 is a perspective view of one of the elements of the present invention;

Figure 4 is a similar view of another element;

Figure 5 is a front view of the element shown

2

in Fig. 3 with record cards associated therewith; and

Figure 6 is a front view of the elements shown in Figs. 3 and 4 associated together when not in use.

Referring in detail to the illustrative construction shown in the drawings, a holder indicated generally by the numeral 10 with which the present invention is employable may comprise an elongated base 11 upon which are mounted transversely a plurality of parallel longitudinally spaced apart rails 12. A pair of side support members 13, somewhat like the covers of a book, are hingedly secured along each longitudinal edge 15 of the base 11 as by hinge straps 14 apertured as at 15 for the passage of retaining screws 16 which pass loosely through the apertures 15, and into the base 11, which may be conveniently formed of wood, somewhat as described and claimed in my co-pending application Serial No. 444,378 filed May 25, 1942, now Patent No. 2,364,640, dated Dec. 12, 1944. The heads of the screws 16 are spaced from the base and may secure thereto finishing plates 17. The longitudinal edges of the base 11 are inclined as at 18 so that the side supports 13 may be inclined with reference to the base as indicated at the right hand side of Fig. 1 or may be vertical thereto as indicated at the left hand side of Fig. 1, these side supports being free to swing from side to side on the base limited by movement of the hinge straps 14 on the screws 16. The side supports 13 are advantageously made of relative heavy fibre board or the like and the hinge straps 14 may be secured thereto as by rivets 19. It will be understood that the hinge straps 14 are spaced between the rails 12 to miss the latter.

Intermediate of the side supports 13 may be a plurality of partition supports 20, conveniently of somewhat lighter fibre board than the side supports 13. The partition supports 20 are desirably removably retained in association with the base 11 as described and claimed in my co-pending application Serial No. 471,549 filed January 7, 1943, Patent No. 2,359,376 dated October 3, 1944 which is a division of my application Serial No. 382,499 filed March 10, 1941 Patent No. 2,326,241 dated August 16, 1943. In general, cylindrical trunnions 21 and 22 at each lower cover of the partition supports and formed from metallic foot parts 23 and 24 respectively are riveted to the partition supports as at 25 and 26 respectively. At one end of the base, the trunnions 21 are extended beyond the partition members to underlie

an over-hanging wall 27 on the base, and, at the opposite end, the trunnions 22 are extended within the vertical projection of the support member to underlie another over-hanging wall 28. A retaining filler block 29 is adapted to be wedged into the space between the ends of the feet 24 and an end wall 30 of the holder. It will be understood that when the filler block 29 is removed, the partition supports may be slid to the right in Fig. 2 to be removed from the base if desired, but when retained on the base as shown, are free to pivot thereon on the axes of the trunnions which latter at the same time are free to roll on the floors 31 and 32 respectively of the channel members 33 and 34 carried by the base at each end transversely thereof and from which are formed the over-hanging walls 27 and 28 respectively. The channel member 34 also conveniently is bent to form the holder end wall 29 as shown.

It will be understood that the purposes of the structure just described, is to mount in upright position a plurality of series of record cards, say, between each of the partition supports 20, and if desired between each of the side supports 13 and the next adjacent partition support 20. Compartments or spaces therebetween are provided for both by the cylindrical trunnions 21 and also by thickened cap strips 35 for each of the supports 13 and 36 for each of the partition supports 20. Only one such card series 37 is here shown for illustrative purpose, and which in this instance comprises a plurality of individual cards 38. As is well known in the art, the lower edges of the cards 38 may be notched as at 39 at regularly spaced intervals thereon so as to engage the rails 12 which may thus retain the cards in a well known over-lapping or echelon arrangement, each card having an exposed so called visible margin 40 when the holder is opened, somewhat like a book, and as more particularly described in my said prior applications.

The present improvements, by which a series of such cards, such as the series 37, may be handled for transfer or other purposes such as making a permanent record of the series by the use of photography, desirably comprises, in accordance, with the present invention, a pair of card handling elements 41 and 42 shown in perspective, respectively, in Figs. 3 and 4, and being what I have here denominated a mounting panel and gripper bar respectively.

Turning first to the mounting panel 41, this desirably includes a panel portion per se 43, which may be conveniently formed of heavy fibre board or the like similar to the card supports, and adjacent the lower margin of which is, suitably secured, a rib 45 of the same material. Spaced at intervals along the outer face of the rib 45 are a plurality of, and, in this instance, four, leaf springs 46, secured as by rivets 47, which, after passing through the spring members, also pass through the rib 45 to further secure the attachment of the rib to the panel 43 as best shown in Fig. 1. The free ends of the leaf springs 46 project upwardly, first bent sinuously into proximity with the panel as at 48, and then flared outwardly as at 49. Over the lower ends of the springs on the outer face of the rib 45, is shown secured, as by gluing, a coaming 50, this coaming being slotted at intervals as at 51 longitudinally opposite the upper end of each spring to permit the said upper end of the spring to play therein. It will be noted that the coaming desirably provides a guard for the free and other-

wise sharp edges of the spring upper ends. The coaming also is recessed along its inner face as at 52 to let thereinto the heads of the rivets 47. At each end the panel 43 is here shown continued downwardly below the rib 45 to provide legs 53 for the mounting panel. The legs 53 serve both to elevate the main part of the panel and also to accommodate the bulge of the sheet series 37 where the overlaps are most numerous adjacent a middle line from front to rear of the holder.

Turning next to the gripper bar 42, this is desirably bifurcated and in this instance comprises a pair of furcations 54 and 55 advantageously made of material similar to that of the panel 43 and of approximately the same length as the panel. The furcation 55 has fixed along its upper margin a filler strip 56 while the narrower furcation 54 is loosely mounted on headed pins 57 which pass loosely through the furcation 54 through the filler strip 56, and through the furcation 55, upon the rear face of which they are riveted as at 58. The side of the filler strip upon which the furcation 54 is mounted is desirable slanted as at 59, and the furcation 54 is pressed against this slanting surface by coil springs 60 disposed between this furcation and the heads of the headed pins 57, thus causing the furcation 54 to flare outwardly and to form with the furcation 55 a normally somewhat inverted V-shape for the gripper bar which assures that the furcations are spaced apart at their lower margins until it is desired to press them together manually on said lower margins, against the resilience of the springs 60, to grip the upper margins of the cards 38, say, of the card series 37. It will be seen that the springs 60, of which there are a number (more than two) spaced along the gripper bar, are free to act independently each of the other and therefore adapt themselves to a card series being normally thicker adjacent its middle than at its ends, the furcations 54 and 55, being of a flexible material; also contributing to this adaptation.

This gripping function of the gripper bar 42 may be made use of as shown in Fig. 1 by first swinging apart the partition supports 20 on each side of the card series 37 which it is desired to handle, for example. By swinging the partition supports apart at this point in the holder the compartment or space therebetween is accessible and the card series 37 is displayed with the exposed margins 40 of the cards facing the operator and with the cards inclined away from the operator so that the exposed margins 40 are readily visible and constitute what at this time may be called a front face of the card series. Before this has been done, however, the card series 37 has first been swung in the opposite direction, that is to be inclined toward the operator by manipulating the partition supports 20, so as to permit placing behind the card series 37 the mounting panel 41, with the legs 53 resting on rails 12. When now the cards are inclined rearwardly again, as already described, the coaming 50 of the mounting panel supports the card series spaced away from the panel 43 per se and making it easy for the gripper bar 42 to be then placed over the upper edges of the cards 38, as is shown in full lines in Fig. 1. When now the operator is ready to lift the card series, the operator may press together, with the fingers, the furcations 54 and 55 so that furcation 54 occupies the position shown in dotted lines in Fig. 1, and thus causing the gripper bar to grip the entire series of

card 38 so that these may be lifted in a body from the rails 12 and placed upon the mounting panel 41.

It has been found that the cards, even if of light sheet material, have sufficient rigidity when lifted in a body as just described to overcome the resilience of the springs 46 and permit the lower edges of the cards to be forced down on the panel 41 until the card lower edges rest upon the rib 45, the upper edge of which 61 thus forms a supporting ledge for the cards, the springs 46 preventing accidental dislodgement therefrom and providing card engaging means carried by the panel and cooperating with the ledge 61. It will now be apparent that the positions of the parts are as shown in Fig. 2, the cards having the same echelon arrangement which they had when resting on the rails 12.

The next step is to remove the mounting panel 41 from the holder and remove the gripper bar 42 from the cards, leaving the cards mounted in echelon arrangement upon the holder as shown in Fig. 5. At this time a photograph may readily be taken of the card series, the exposed or visible margins of which may display, in addition to indexing data, various record summaries relating to record keeping purposes. It will be understood that the cards have a blank lower margin which only is concealed by the coaming 50 and which is of no interest in the photograph. It will also be apparent that the cards and mounting panel shown associated in Fig. 5 may be handled freely without danger of the cards being dropped from the holder or being displaced thereon.

Here again, since the springs 46 are independent in their action, the usual bulge which occurs at the center portion longitudinally of the card series because of the greater number of card overlaps at this point, is accommodated, without detracting from the holding effect of the independent springs 46 at the ends of the cards series.

It will also be apparent from Fig. 5 that the cards desirably project slightly above the upper edge of the mounting panel 41 so that the cards may be rifled by the operator for individual examination of the portions thereof which are normally concealed. Also by reason of this extension of the cards above the panel, when it is desired to return the card series to the file holder 10, replacement of the gripper bar 42 on to the upper edges of the cards is facilitated. Thereupon, the panel having now been restored to the position in the holder as shown in Figs. 1 and 2, with cards thereon, the furcations 54 and 55 of the gripper bar are again pressed together and the cards lifted from the ledge 61, against the frictional pressing action of the springs 46. The cards may be then replaced upon the rails 12 in their original position whereupon the gripper bar is removed and likewise the panel 41, leaving the card series 37 exactly as it was originally in the holder and with the same echelon arrangement of the individual cards in the series.

It will be readily apparent that the gripper bar 42 may be manipulated by the thumb and index fingers of each hand as indicated at A (Fig. 2) leaving the other fingers free to be pressed against the upper edge of the panel 43 when it is desired to withdraw the cards from the panel. Also it will be apparent that when the cards are relatively large, with only a few cards in a series, they may be manipulated to and from the

mounting panel 41 without the use of the gripper bar 42.

When the panel and gripper bar are not in use, they may be secured together as shown in

5. Fig. 6 by forcing the furcation 55 down onto the ledge 61 of the panel where it will be held by the action of the springs 46; just as the cards are held, until it is desired to separate the panel and gripper bar for use as described.
10. So constructed and arranged, it will be seen that either 43 or 55 is a panel insertable between series of cards, that either 46 or 60 are independent springs spaced therealong for maintaining the cards in abutment with a rib on the panel 15. (either 45 or 56 being such a rib), and that either 50 or 54 is an auxiliary panel, the cards being received between the pair of panels 43 and 50 or 55 and 54 or between both pair simultaneously, as the case may be.
20. It will be understood that the invention is not limited to details of construction shown for illustrative purpose. Furthermore, it is not intended to be understood that all features of the invention must be used conjointly, since various combinations and sub-combinations may at times be advantageously employed. Such changes may be made as fall within the scope of the following claims without departing from the invention.

Having described my invention, I claim:

30. 1. In a card handling device, the combination of a panel, a rib along the lower edge of the panel providing an upwardly facing ledge thereon, a series of leaf springs secured to the outer face of the rib and having their free ends projecting there- 35. above into proximity with the panel, the springs being spaced along the panel longitudinally and having their said free ends turned outwardly, a coaming secured to the outer face of said rib and over the lower ends of the springs, said coaming being slotted at intervals longitudinally opposite the upper end of each spring to permit the upper ends of the springs to play therein, said coaming providing a guard for the free edges of said spring upper ends, and legs at each end of the panel provided by downwardly extending continuations thereof below said rib.

40. 2. In a card handling device, the combination of a panel, a rib along the lower edge of the panel providing an upwardly facing ledge thereon, a series of leaf springs secured to the outer face of the rib and having their free ends projecting thereabove into proximity with the panel, the springs being spaced along the panel longitudinally and having their said free ends turned inwardly and then outwardly, a coaming secured to the outer face of said rib and over the lower ends of the springs, said coaming being slotted at intervals longitudinally opposite the upper end of each spring to permit the upper ends of the springs to play therein, said coaming providing a guard for the free edges of said spring upper ends, wherein the springs have rivets passing therethrough and through the rib and panel and the coaming is recessed on its inner face to let the rivets thereinto.

45. 3. In a card handling device for series of record cards mounted in echelon arrangement, the improvement of a panel insertable between card series having a ledge along its lower margin for supporting the lower edges of the cards when a series of said cards is placed thereon, and card engaging means carried by the panel for maintaining the cards releasably on said panel, wherein the card engaging means comprises a plurality of independent spring pressed members adapt-

ed to press against the faces of the cards and to press the cards against said panel, said members being of cam formation and arranged to be resiliently retracted by movement of the cards between said members and said panel.

4. In a card handling device for record cards mounted in echelon arrangement and having partition sheets separating series of cards, the improvement of a panel insertable between card series having a ledge along its lower margin for supporting the lower edges of the cards when a series of said cards is placed thereon, and card engaging means carried by the panel for maintaining the cards releasably on said panel, wherein the card engaging means comprises a plurality of independent spring pressed members adapted to press against the faces of the cards and to press the cards against said panel, and wherein there is a coaming extending along the outer edge of said ledge into which said spring pressed members are let and for protecting said members.

5. In a card handling device comprising a panel having a rib thereon for abutting the edges of the cards when a series of cards in echelon arrangement is placed thereon distributed therealong, resilient card engaging means carried by the panel for maintaining the cards releasably on said panel in abutment with said rib and including more than two independent spring means spaced longitudinally therealong whereby said independent spring means adapt themselves to variations in thickness of the series of cards at the ends of the panel and adjacent the middle thereof, and a coaming spaced from said first mentioned panel by said rib, the cards being received between said coaming and panel.

6. In a card handling device, a panel insertable between card series having a ledge thereon adjacent its lower edge for abutting the edges of the cards when a series of cards is placed there-

5 on distributed therealong a series of cards in echelon arrangement on said ledge, resilient card engaging means carried by the panel for maintaining the cards releasably on said panel and including more than two independent spring means spaced longitudinally therealong resiliently retractable by the lower edges of the cards moving into the position on the ledge and whereby said independent spring means adapt themselves to variations in thickness of a series of cards at the ends of the panel and adjacent the middle thereof, and spaced apart supporting means for the panel below the ledge, said panel being of less vertical height than the cards whereby the upper edges of the cards may be rifled.

10 15 ALFRED M. MARTIN.
